UNITED STATES PATENT OFFICE

REMMEL HANLEY HILL, OF COLUMBIA, MISSOURI

MEDICINE DISPENSER

Application filed March 26, 1929. Serial No. 350,043.

This invention relates to an improved laboratory appliance especially designed for conveniently dispensing various kinds of medicine, and it has more particular reference to a structure which is particularly suitable for use in dental operating rooms or laboratories.

The principal novelty is predicated upon a structure which is so made as to systematically accommodate distinguishable medicine containers, in order that these containers may be held in a concentrated and orderly fashion to facilitate the use and application of the different medicaments.

Stated otherwise, I have developed a simplified rack equipped with a plurality of individual medicine bottle holders, means being provided on said rack for separately or simultaneously uncovering the bottles to expedite selection and application of the different species of medicine contained in the respective bottles.

In carrying out this idea, I have constructed a compact and convenient appliance which is characterized by an arrangement of details, so associated and cooperating as to promote efficiency, cleanliness, sanitation and unconfused selection.

Other features and advantages will become more readily apparent from the following description and drawings.

In the drawings:

Figure 1 is a top plan view of the complete structural organization as made in accordance with the present invention.

Figure 2 is a fragmentary end view of one portion of the structure showing two of the units.

Figure 3 is a transverse vertical section, taken approximately upon the plane of the line 3—3 of Figure 1, representing one of the medicine bottles with the cover or cap closed, and

Figure 4 is a view based on Figure 3, showing the caps lifted to uncover the bottles.

Figure 5 is a perspective view of a carrier bar.

Figure 6 is a top plan view of a bottle cap clamp.

Figure 7 is a fragmentary view of a portion of the tray showing the bottle holder.

As before intimated the structure is provided with a suitable support here shown in the form of a rack generally designated by the reference character 8. As is clear from Figures 3 and 4, it is convenient to provide a rack which includes a horizontal tray 9, open at its front, and an upstanding back wall 10, this wall being joined by end flanges 11 to the end walls of the tray. Thus, the rack forms not only a support for the mechanism but a sort of enclosure or casing. Incidentally, in practice, it may be found desirable to close the entire structure in a protective housing to protect against dust accumulations. The housing might well be a transparent glass casing or the like. However, this constitutes no part of the invention.

In accordance with this invention, I make provision for a multiplicity of containers on this rack and the idea is to concentrate or arrange these in an orderly or easily collected manner in order to expedite the removal and use of the various medicines. In this connection, it is advisable to mention that the medicine usually applied by raw cotton held in tweezers or similar implements and by simply opening the bottle and dipping the raw cotton into the medicine, application is expedited. With the usual arrangement, the bottles are arranged in a cabinet or on a table and become misplaced and frequently not in a convenient position for selection and rapid application, thus causing inconveniences. With this arrangement, the rack is made into distinguishable sections or units, and each is composed of a duplicate mechanism.

For this reason, a description of one unit will suffice for all. For example, by referring to Figure 3, it will be seen that the reference character 12 designates a bottle container or holder. This is rigidly fastened to the tray and includes upstanding spring clips for resiliently gripping the body portion 13 of the bottle. As shown in Figure 4, the bottle has conical or bevelled neck 14 to accommodate the removal closing cap 15. In accord-

ance with the invention, a special clamp is provided for embracing this cap. The clamp as seen in Figure 6 comprises a bail 16 and an annulus 17 embraces the cap. Means is provided for cooperation with this cap clamp for lowering and raising the cap to open and close the bottle.

In accomplishing this task, I have found it convenient to provide stationary guide rods these being fastened at their lower ends to the tray and at their upper ends to the back 10, being located in spaced parallelism on opposite sides of the bottle and bottle holding means. These guide rods 18 function as 15 tracks for a lifting rod. Referring to Figure 5 it will be seen that this rod is designated by reference character 19, that it is formed at one end with the guide sleeve 20 which is slidable on one of the rods 18 and is formed 20 on its opposite end with the fork 21 which is slidably cooperable with the complemental guide rod.

Adjacent the sleeve is a depending slidable attaching ear 22. As shown in Figure 4, an 25 operating link 23 is connected with and depends from the ear and is connected with the inner end of a hand manipulated operating lever 24. This lever is pivotally mounted on a post 25. The outer end is formed 30 into a finger piece. Thus, it will be seen that when the parts are assembled, and the bottle is closed, these parts assume the relationship seen in Figure 3. By depressing the lever, however, the parts assume the relationship seen in Figure 4, at which time the link 35 23 lifts the bar 19, and the bar in turn lifts the cap 16, through the medium of the clamp which embraces it. Then the contents of the 40 bottle 13 is exposed for expeditious application of the medicine.

As soon as the lever is released, the weight of the parts causes them to assume their original relationship as represented in Figure 3. Thus the device is substantially automatic or self closing. Frequently it becomes necessary to use a combination of medicines and this makes it advisable to provide means for simultaneously opening all of the bottles. I have accomplished this by simply providing a U-shaped pivoted frame 26, mounted 45 on the rack in such a way that the bight portion comes down in operating contact with the various operating levers 24.

Hence, by adjusting this frame and pushing it down, all of the levers are simultaneously operated to open the caps of all bottles. Consequently, I have developed a novel mechanism for simultaneous or selective uncovering of the bottles. Incidentally it is to be noted that the bottles are attached to the 50 rack by resilient retaining devices which permit removal of the bottles for expeditious refilling or washing.

From the foregoing description and drawings, it will be seen that I have evolved and

produced a novel mechanical structure for convenient employance in a dental laboratory or the like. The structure is efficient in performance, positive and dependable in action, quite smooth and quiet in operation, practical in every way, and otherwise adapted for fulfilling the requirements of an invention of this class in a satisfactory manner.

It is thought that by considering the description in conjunction with the drawings, persons familiar with inventions of this general type will be able to obtain a clear understanding of the same. Therefore a more lengthy description is regarded as unnecessary.

Minor changes in the shape, size, and rearrangement of details coming within the field of invention claimed may be resorted to, in actual practice, if desired.

I claim:

1. In a medicine dispensing appliance of the class described, a rack, a plurality of stationary individual bottle holders on said rack for the reception of medicine bottles, each bottle having a neck, caps designed for removable placement on said necks, and mechanism on said rack for selectively raising the caps from the necks either singly or collectively.

2. In a dental appliance of the class described, a rack, a stationary bottle holder on said rack adapted to receive a bottle, a removable cap for said bottle, stationary guide rods attached to the rack on opposite sides of the bottle holder, a carrier and lifting rod 100 slidably mounted on said guide rods, said cap being suspended from said lifting rod, a pivotally mounted operating lever, and an operating connection between the lever and lifting rod.

3. In an appliance of the class described, a rack, a resilient stationary bottle holder on said rack, a pair of vertically spaced parallel guide rods on the rack on opposite sides of the bottle holder, a carrier rod having a sleeve mounted for sliding on one guide rod, and a fork embracing the complemental guide rod, a bottle cap clamp carried by said last named rod, pivoted operating lever, and a link connection between said lever and said last named rod.

In testimony whereof I affix my signature.
RÉMMEL HANLEY HILL.
